UNITED STATES PATENT OFFICE.

WILLIAM H. KNAPP, OF GALESBURG, MICHIGAN.

GRAIN PACKER AND CARRIER.

SPECIFICATION forming part of Letters Patent No. 435,143, dated August 26, 1890.

Application filed March 17, 1890. Serial No. 344,217. (No model.)

To all whom it may concern:

Be it known that I, WILLIAM H. KNAPP, a citizen of the United States, residing at Galesburg, county of Kalamazoo, State of Michigan, have invented a new and useful Grain Packer and Carrier, of which the following is a specification.

This invention more particularly relates to devices known as "grain packers and carriers," either for moving the grain along the platform or for packing it back beneath the needle-bar in grain-harvesters in a compact condition ready for binding.

The object of the invention consists in a construction in which twolapping rotary disks or wheels are employed, to which wheels the ends of the rake-heads are attached, one end being attached to one disk and the other end to the other disk in the order and arrangement below described, and in which the rakes are always carried in the same position during their different movements downward, backward, and upward, in which movements they enter the grain, carry it from one place to another, and rise out of the grain.

No harvester is here illustrated, but simply the mechanism or apparatus for carrying or packing the grain, from the fact that the use of such devices are so well understood.

30 In the drawings forming a part of this specification, Figure 1 is a sectional elevation taken on line 3 3 in Fig. 2. Fig. 2 is a plan view of Fig. 1.

Referring to the lettered parts of the drawings, A is the frame, in which thelapping-wheels B and B' are journaled, the axis of the wheel B being shown at E and the axis of the wheel B' consisting of the shaft D, to which power is applied when in operation.

40 The rakes consist of the head C and the vertical teeth a, projecting from each end of said head and at right angles thereto. One end of these rake-heads is pivoted to the wheel B' at i, and the other end is pivoted to the

45 wheel B at e. Three of these rakes are used, as in Fig. 1, but more may be employed. The length of the teeth a must be governed according to the distance between the pivots e of one rake-head and those of another, so

50 that the ends of the rake-teeth will not con-

flict therewith. The movement of these rakes is illustrated in Fig. 1 in dotted position, the lower dotted rake being in the position it would occupy in the grain when carrying the same or when packing it beneath the needle-bar ready for binding.

When the carrier and packer is used in the position shown in Fig. 1, the harvester-platform or the binding-table, as the case may be, will be directly beneath the ends of the 60 lower dotted rake-teeth; but this carrier and packer may be used the other side up, so that the teeth will be thrust up into the grain instead of down into it, or it may be used at different angles—as, for instance, in grain-elevators—whereby the grain may be carried up an incline or perpendicular. A series of these rakes and their wheels may be employed in a single construction side by side or end to end. Each end of the rake-heads may be provided (by making their pivotal ends of sufficient length laterally) with as many teeth as desired, only one at each end being here shown, and in such a case of course the wheels B and B' would have to be farther apart.

75 While I have described this apparatus as being adapted for use in carrying and packing grain, it may be employed in carriers and elevators for other purposes and in carrying paddles through the water for propelling boats 80 to which said apparatus may be attached, or, in fact, in any device wherein the heads C and the teeth a or projections are operated by the wheels B and B' upon the principle herein illustrated. The parts C, I have termed 85 the "rake-heads," and I have termed the parts a "rake-teeth;" but in constructions in which these rakes are not employed to carry or pack grain the part C should be termed a "bar," and the teeth a should be termed "right-angled 90 projections."

Having thus described my invention, what I claim as new, and desire to secure by Letters Patent of the United States, is—

1. A carrier or packer consisting of two 95 separated lapping revoluble disks and the bars provided with the right-angled projections, one end of the bars being pivoted to one disk and the other end to the other disk, substantially as set forth.

2. The combination of a grain-harvester
and the grain carrier and packer consisting
of the lapping separated revoluble disks and
the rake-heads provided with the teeth, one
5 end of the rake-heads being pivoted to one
disk and the other end to the other disk, sub-
stantially as set forth.

In testimony of the foregoing I have here-
unto subscribed my name in presence of two
witnesses.

WILLIAM H. KNAPP.
